PROCESS OF REFINING VEGETABLE OILS

Benjamin Clayton, Houston, Tex.

Application January 4, 1939, Serial No. 249,284

9 Claims. (Cl. 260—425)

This invention relates to the refining of vegetable oils, and more particularly to a process in which an alkaline reagent, which decreases the emulsifying properties of gummy materials contained in the oils, is added thereto prior to the addition of a caustic alkali so as to decrease the refining losses of the process in refining of vegetable oils.

Vegetable oils in the form received by the refiners usually contain relatively large amounts of gummy materials, such as, for example, phosphatides, proteins, resins, carbohydrates, etc. An alkaline refining reagent, when added to the oil, neutralizes the free fatty acids thereof and precipitates the gums to form soap stock which can be continuously centrifugally separated from the oil. In order to substantially completely neutralize the free fatty acids and decolorize the oil, caustic alkalies are ordinarily employed as refining reagents. An excess thereof is used to react with color impurities. This excess also attacks neutral oil to produce less valuable soap, resulting in a refining loss. Also, the gummy materials present in the soap stock cause a large amount of neutral oil to be entrained therein. The entrained neutral oil also constitutes an extremely important refining loss.

The removal of the gums by a degumming step prior to alkali refining has been suggested, but in conventional degumming steps considerable oil is entrained in the gums separated from the oil prior to alkali refining. Also, the soap stock resulting from alkali refining, being relatively free of gums, is difficult to separate cleanly from the oil. It has been found that the employment of an alkali which will not saponify neutral oils, for example, sodium carbonate, not only reduces refining losses resulting from the saponification of neutral oil but causes less neutral oil to be entrained in the soap stock. Such alkalies as sodium carbonate apparently reduce or destroy the emulsifying properties of the gums, that is to say, the gums are fixed in non-emulsifying form.

Such non-saponifying alkaline reagents, however, do not completely neutralize the free fatty acids nor do they appreciably reduce the color of oils requiring decolorizing even if an excess is employed. This is particularly true with sodium carbonate, which has been found to be the most efficient gum fixing reagent. Carbon dioxide gas tends to form unless extremely large excesses are employed or the temperature in the process is kept below that which produces satisfactory refining. The carbon dioxide becomes dissolved in the oil and water present in the process, setting

up an equilibrium which prevents complete neutralization of the free fatty acids. Also, this gas becomes occluded in the soap stock, rendering the same lighter in weight and extremely difficult to cleanly separate from the oil.

In accordance with the present invention, it has been found that sodium carbonate may be employed in combination with caustic alkalies not only to reduce the neutral oil entrained in the soap stock but to decrease the loss due to attack on the oil by the caustic alkali. Since the gums may be present during refining, any losses due to prior degumming of the oils are avoided.

The sodium carbonate, preferably in aqueous solution, is added to the oil prior to adding the caustic alkali, and fixes the gums so that their emulsifying properties are diminished and the amount of neutral oil entrained in the soap stock is lessened. It is added to the oil under temperature conditions or in sufficient excess to prevent the formation of any substantial amount of carbon dioxide. As the sodium carbonate does not attack neutral oil, the mixing with the sodium carbonate can be done either in flow or as a batch operation. At least a part of the free fatty acids are neutralized to form soap, and the resulting mixture of oil and soap stock is then admixed with caustic alkali, for example, caustic soda. The caustic soda completes the neutralization of the free fatty acids, and reduces the color of the oil. The resulting soap stock can be separated from the oil with very little contained neutral oil. The presence of relatively large amounts of sodium carbonate also appears to inhibit the attack of the caustic alkali upon neutral oil, so that refining losses due to saponification of neutral oil are also reduced.

It is, therefore, an object of the present invention to provide a process of refining vegetable oils in which a non-saponifying alkaline reagent is employed to fix the gums contained in the oil in non-emulsifying form prior to the addition of a caustic alkali refining reagent.

Another object of the invention is to provide a process of refining vegetable oils in which oil entrained in the soap stock resulting therefrom, due to the presence of gums in the oil, is reduced.

A further object of the invention is to provide a process for the alkaline refining of vegetable oils, in which a non-saponifying alkali is employed in combination with a caustic alkali in order to reduce refining losses due to saponification of neutral oil and entrainment of a neutral oil in the soap stock separated from the oil. Other objects and advantages of the invention

tion will appear in the following description of preferred embodiments made in connection with the attached drawing, of which:

Figure 1 is a schematic diagram of apparatus suitable for carrying out the process in accordance with the present invention; and

Figure 2 is a similar diagram of a modified apparatus.

Referring to the drawing, and more particularly to Figure 1, crude oil may be withdrawn from a source of supply shown as a tank 10 by means of a proportioning pump 11, and delivered through a heat exchange device 12 to a mixer 13. The heat exchange device 12 preferably includes a coil 14 through which the oil is passed, the coil being surrounded by a casing 15 through which any desired heating or cooling medium may be circulated.

An aqueous solution of a non-saponifying alkali, for example, soda ash, is withdrawn from a source of supply shown as a tank 16 by a proportioning pump 17 and delivered to the mixer 13. The mixer 13 is preferably of the type in which the alkaline reagent is injected at right angles into a flowing stream of the oil and is preferably of the type disclosed in my copending application Serial No. 190,673, filed February 15, 1938, although any type of closed flow mixer, such as a mechanical agitator, may be employed. The non-saponifying alkali reacts with at least a portion of the free fatty acids in the oil and precipitates gums to form soap stock. More important, it fixes the gums contained in the soap stock in non-emulsifying form by inhibiting their emulsifying properties.

The mixture of oil and soap stock is then passed through a second heat exchange device 18 including a coil 19 and a casing 20 through which a heat exchange medium may be passed. The oil leaving the heat exchange device 18 is delivered to a second mixing device 21 which may be similar to the mixing device 13. An aqueous solution of a caustic alkali such as caustic soda is withdrawn from a source of supply shown as a tank 22 by a proportioning pump 23 and delivered to the mixer 21. The proportioning pumps 11, 17 and 23 are shown as being driven by a variable speed electric motor 24 with variable speed devices 25 and 26 positioned between the pumps 11 and 23, respectively, although any other type of suitable proportioning mechanism capable of accurately proportioning streams of the various materials and delivering them under pressure to the mixing devices may be substituted therefor.

The caustic soda solution delivered to the mixer 21 completes the neutralization of the free fatty acids, and reacts with coloring materials present in the oil to decolorize the oil. The resulting mixture of oil and soap stock is then preferably passed through a third heat exchange device 27 including a coil 28 and a casing 29 through which a heat exchange medium may be passed. The resulting mixture is then delivered to a continuous centrifugal separator 30 in which the soap stock is separated from the oil and delivered as the heavy effluent through a spout 31 into a receiver 32. The oil is delivered as the light effluent through a spout 33 into a receiver 34. The centrifugal separator 30 is preferably of the heated type disclosed in Patent No. 2,100,277, granted November 23, 1937.

In the above process, the heat exchanger 12 is employed to bring the oil to a mixing temperature found most effective for the particular oil being treated. This temperature is ordinarily relatively low, for example, between 70 and 100°

F., in order to prevent the formation of carbon dioxide when soda ash is employed, although with increased amounts of soda ash this temperature may be somewhat higher. In general, better mixing and more complete neutralization of the free fatty acids is accomplished at the higher temperature, although this will vary with the nature of the oil such as its viscosity and amount of gums contained therein. The amount of soda ash employed is usually that necessary to be 10 chemically equivalent to the free fatty acids in the oil, although lesser amounts may be employed if the temperature of mixing is relatively low, and, on the other hand, excesses of soda ash as great as or slightly greater than twice the amount 15 chemically equivalent to the free fatty acids may be employed to insure that no carbon dioxide is formed.

The heat exchanger 18 is employed to bring the mixture of oil and soap stock from the mixer 20 13 to the temperature of mixing with caustic alkali found most effective for the particular oil being treated. This temperature will vary with different oils being treated, depending upon the amount of gums contained therein, the amount of 25 free fatty acids and the viscosity of the oil. That is to say, the temperature of mixing will vary from 70° F. or lower to as high as 160° F. Thus, the most effective temperature for mixing in the mixer 21 may be lower or higher than the temperature found effective for mixing in the mixer 13, or, in some instances, may be the same. In the latter case the heat exchanger 18 may be eliminated or alternatively employed to provide a treating time, for example, 2 to 5 minutes, so as 30 to insure fixing of the gums in non-emulsifying form as well as better neutralization of free fatty acids. The time of treating in the coil 19 of the heat exchanger 18 may be as long as necessary, depending upon the oil being treated, as the alkaline reagent present therein does not attack 40 neutral oil. However, this time of treatment is correlated with the temperature to prevent formation of any substantial quantities of carbon dioxide. It is preferred to employ a relatively 45 concentrated aqueous solution of the sodium carbonate in order to cut down the amount of water in the process and therefore the total amount of soap stock separated from the gum separates as part of the soap stock. In general, the greater 50 the amount of soap stock the more oil entrained therewith, and as the gums are rendered relatively non-emulsifying in the present process, the viscosity of the soap stock is ordinarily sufficiently low to provide efficient separation even 55 though the amount of water therein is relatively small.

The amount and concentration of caustic alkali employed should be sufficient to complete the neutralization of the free fatty acids, and, 60 with highly colored oils, provide an excess sufficient to react with the color impurities to decolorize the oil. Since all of the sodium carbonate employed is ordinarily not effective to neutralize free fatty acids, usually considerably 65 greater amounts of combined soda ash and caustic soda must be employed than the amount chemically equivalent to the free fatty acids. The caustic soda solution is also preferably relatively concentrated in order to cut down the 70 amount of water in the process, but the concentration of this solution will again depend upon the amount of water necessary to provide for continuous and clean separation of the soap stock from the oil. With certain oils it is found that 75

a relatively low temperature of mixing with the caustic soda is preferable, as color reactions apparently proceed with greater rapidity under low temperature conditions, although with other oils relatively high temperatures in the mixer 21 secured by the heat exchanger 18 have been found to provide for better separation in the centrifugal separator.

The heat exchanger 27 may be employed to adjust the temperature of the mixture leaving the mixer 21 to that found to give most effective separation for the particular oil being treated. This separation temperature is usually found to lie between 110 and 160° F. and will vary with different oils. If the temperature of mixing in the mixer 21 happens to be that found most effective for separation in the centrifugal separator 30, the heat exchanger 27 may be omitted or employed to give a treating period without change of temperature. This procedure has been found desirable with certain oils in order to provide time for color reaction and also condition the mixture for centrifugal separation, but in general should be made as short as possible, for example, 2 to 5 minutes, as the caustic soda present in the mixture will also attack neutral oil. The prior addition of the sodium carbonate appears to inhibit this reaction, but the saponification of neutral oil does take place to some extent and increases with length of time of treatment and with increased temperature in the heat exchanger 27. By employing the heated centrifuge referred to, at least a portion of the heat required for separation with a particular oil may sometimes be imparted to the oil within the separator itself, thus cutting down the length of time the oil is in contact with the caustic soda at elevated temperatures. In any event, the heating of the soap stock layer adjacent the wall of the centrifugal bowl in the heated centrifugal separator referred to provides for the uniform discharge of the soap stock from the separator.

The apparatus disclosed in Figure 2 is similar to that in Figure 1, except that provision is made for mixing the soda ash with a batch of the crude oil. This apparatus may include a vessel 35 which may be similar to neutralizing kettles commonly employed in the batch refining of vegetable oils. The vessel 35 is preferably provided with a mechanical agitator driven from any suitable source of power 37 and may be further provided with a heating jacket 38 through which any desired heating medium may be circulated. Crude vegetable oil may be delivered into the vessel 35 through a pipe 39 and the non-saponifying neutralizing reagent delivered through a pipe 40. In usual operations, a body of oil is first delivered into the kettle and then an aqueous solution of soda ash run in through the pipe 40 during agitation by means of the agitator 36 until the required amount of soda ash has been added. At least a portion of the fatty acids are neutralized, and the gums precipitated and fixed in non-emulsifying form, thereby forming soap stock in the vessel 35. The temperatures of mixing are preferably substantially the same as those discussed with respect to the mixer 13 in Figure 1, and the amount of soda ash added may be also substantially the same as that discussed with reference to the process of Figure 1. Conditions of mixing in the vessel 35 are carried on so as to avoid the formation of any substantial amounts of carbon dioxide when soda ash is employed, and mixing is continued until substantially all of the gums are precipitated. Sufficient

agitation by the agitator 36 is then continued to prevent stratification of the soap stock in the kettle 35, and the resulting mixture is withdrawn from the vessel 35 by the proportioning pump 41 and delivered through a heat exchange device 42 to a mixer 43. Caustic soda solution is withdrawn from a source of supply shown as a tank 44 by means of a proportioning pump 45 and delivered to the mixer 43. As shown in Figure 1, the proportioning pumps 41 and 45 may be driven by a variable speed electric motor 46 with a variable speed device 47 positioned between the pump 41 and the motor 46. The mixture produced in the mixer 43 is then preferably passed through a heat exchange device 48 and delivered to a continuous centrifugal separator 49 in which the soap stock is separated from the oil and delivered as the heavy effluent through a spout 50 into a receiver 51. The refining oil is delivered as the light effluent through a spout 52 into the receiver 53.

The process carried out in the apparatus of Figure 2 after the non-saponifying alkaline reagent has been mixed with the oil may be entirely similar to that carried out in Figure 1. That is to say, the heat exchangers 42 and 48, the mixer 43 and the centrifugal separator 49 of Figure 2 may be the same and may be employed for the same purposes as the heat exchangers 18 and 27, the mixer 21 and the centrifugal separator 30, respectively, of Figure 1. In either case, the mixing of the non-saponifying alkali with the oil prior to adding the caustic alkali precipitates the gums and inhibits their emulsifying properties and also inhibits the attack on the neutral oil by the caustic alkali subsequently admixed therewith. The preferred non-saponifying alkali is the soda ash above referred to, as this material is available in large quantities at small cost and also appears to be a better inhibitor of the emulsifying properties of the gums and saponifying power of the caustic alkali upon the oil. However, other non-saponifying alkalies such as sodium silicate, trisodium phosphate and equivalent potassium salts as well as other alkali metal salts of weak acids may be employed with satisfactory results. The preferred caustic alkali is caustic soda, although it is possible to employ other caustic alkalies such as caustic potash. In any case, the refining losses due to entrainment of neutral oil in the soap stock and also due to attack on neutral oil by the caustic alkali are reduced over prior processes.

While the addition of the caustic alkali subsequent to mixing with the non-saponifying alkali more effectively inhibits the emulsifying properties of the gums, it is recognized that improved results over conventional refining processes can be produced by adding the non-saponifying alkali with or after the addition of the caustic. Thus a mixture of non-saponifying alkali such as sodium carbonate and a caustic alkali such as caustic soda may be added in flow, such as at 21 in Figure 1, or mixed with the oil in the tank 35 of Figure 2 and the caustic soda tank 44 and mixer 43 of this figure eliminated. The emulsifying properties of the gums in the mixture are inhibited so as to provide more effective separation, and by employing less caustic soda than the amount necessary for complete refining when caustic soda is used alone, saponification of neutral oil is also reduced. When the processes of the present invention are properly carried out as above described, sodium bicarbonate, which will not saponify neutral oil, is formed but no substantial

amount of carbon dioxide is evolved, so that effective separation of the soap stock is accomplished without substantial entrainment of neutral oil in the soap stock.

5 While I have disclosed the preferred embodiment of my invention, it is understood that the details thereof may be varied within the scope of the following claims:

I claim:

10 1. A continuous process of refining vegetable oils, which comprises, adding to a vegetable oil containing gums and free fatty acids a non-saponifying alkali in an amount sufficient to partly neutralize the free fatty acids and inhibit the emulsifying properties of the gums and to produce soap stock incapable of satisfactory centrifugal separation, thereafter continuously, as a stream, adding sufficient caustic alkali to the resulting mixture to substantially completely neutralize the free fatty acids and to produce soap stock of increased centrifugal separability and continuously centrifugally separating the resulting soap stock from said oil.

25 2. A continuous process of refining vegetable oils containing gums and free fatty acids, which comprises, mixing sufficient sodium carbonate with said oil to at least partly neutralize the free fatty acids and fix said gums in non-emulsifying form, thereafter mixing a flowing stream of the resulting mixture with a flowing stream of an aqueous solution of caustic alkali in an amount sufficient to substantially completely neutralize the free fatty acids and to continuously condition the soap stock for centrifugal separation, and continuously centrifugally separating the resulting soap stock from neutral oil.

35 3. A continuous process of refining vegetable oils containing free fatty acids, gummy materials, and coloring impurities, which comprises, mixing an aqueous solution of sodium carbonate with said oil in sufficient amount and concentration to neutralize at least a portion of the free fatty acids and inhibit the emulsifying properties of said gummy material, thereafter admixing a flowing stream of the resulting mixture with an aqueous solution of caustic soda in sufficient amount and concentration to substantially completely neutralize the free fatty acids and react with said coloring impurities to reduce the color 45 of the oil and to continuously condition the soap stock for centrifugal separation, and continuously centrifugally separating the resulting conditioned soap stock from said neutral oil whereby the amount of neutral oil entrained in said soap 50 stock is minimized.

55 4. A continuous process of refining vegetable oils, which comprises, adding to a vegetable oil containing gums and free fatty acids a non-saponifying alkali in an amount sufficient to partly neutralize the free fatty acids and inhibit the emulsifying properties of the gums, thereafter adding, as a stream, sufficient caustic alkali to the resulting mixture to substantially com-

pletely neutralize the free fatty acids and to continuously condition the soap stock for centrifugal separation and continuously centrifugally separating the resulting soap stock from said oil at a temperature facilitating such separation.

5 5. A continuous process of refining vegetable oils, which comprises, adding to a vegetable oil containing gums and free fatty acids a non-saponifying alkali in an amount sufficient to at least partly neutralize the free fatty acids and inhibit the emulsifying properties of the gums, thereafter adding a stream of an aqueous solution of caustic alkali to a stream of the resulting mixture to substantially completely neutralize the free fatty acids, and continuously centrifugally separating the resultant soap stock from said oil.

10 6. A continuous process of refining vegetable oils, which comprises, adding to a vegetable oil containing gums and free fatty acids a non-saponifying alkali in an amount sufficient to at least partly neutralize the free fatty acids and inhibit the emulsifying properties of the gums, thereafter adding sufficient caustic alkali to the resulting mixture to substantially completely neutralize the free fatty acid, heating a stream of said mixture to a temperature facilitating centrifugal separation, and continuously centrifugally separating the resultant soap stock from said oil.

15 7. A continuous process of refining vegetable oils containing gums and free fatty acids, which comprises, mixing sufficient sodium carbonate with said oil to at least partly neutralize the free fatty acids and fix said gums in non-emulsifying form, thereafter continuously admixing a stream containing sufficient caustic alkali with said oil and sodium carbonate to substantially completely neutralize the free fatty acids and separating the resulting soap stock from neutral oil.

20 8. A continuous process of refining vegetable oils containing gums and free fatty acids, which comprises, mixing sufficient aqueous solution of sodium carbonate with said oil to at least partly neutralize the free fatty acids and fix said gums in non-emulsifying form, thereafter mixing a flowing stream of the resulting mixture with a flowing stream of an aqueous solution of caustic alkali in an amount sufficient to substantially neutralize the free fatty acids, heating the resulting stream to a temperature facilitating separation, and continuously centrifugally separating the resulting soap stock from neutral oil.

25 9. A continuous process of refining vegetable oils containing free fatty acids, which comprises, mixing sufficient sodium carbonate with said oil to neutralize a major portion of the free fatty acids, thereafter adding sufficient caustic alkali to substantially completely neutralize the free fatty acids, and separating the resulting soap stock from the oil.

BENJAMIN CLAYTON.
